(57) **CLAIM**

We claim the ornamental design for a high velocity fan, as shown and described.

DESCRIPTION

FIG. 1 is a front perspective view of the high velocity fan device;

FIG. 2 is a rear perspective view of the high velocity fan device;

FIG. 3 is a front elevational view of the high velocity fan device;

FIG. 4 is a rear elevational view of the high velocity fan device;

FIG. 5 is a side elevational view of the high velocity fan device;

FIG. 6 is a side elevational view of the opposed side of the high velocity fan device;

FIG. 7 is a top view of the high velocity fan device; and,

FIG. 8 is a bottom view of the high velocity fan device.
